UNITED STATES PATENT OFFICE

BRAYTON M. PERKINS, OF MOUNDS, UTAH

ORDER CRANE

Application filed April 16, 1929. Serial No. 355,444.

The present invention relates to an order crane and is used for catching train orders and messages by a moving train and the prime object of the invention is to eliminate the danger to the operators who have to hand them up to the fast moving train and the danger to the trainman who has to catch them and the device also eliminates delay to trains on account of missing the hoop and having to stop which often happens when hooping them up by hand.

Most all railroads hoop up their orders and messages by hand, which is dangerous to all concerned.

Another important object of the device is for a hoop to be positioned in a given place and as it is taken out another hoop is thrown in the same place or position until the required number have been caught. Some trains require four or five hooks but mostly two or three according to the rules of the respective railroads.

Another very important object of the invention resides in the provision of an order crane of this nature which is exceedingly simple in its construction, inexpensive to manufacture, strong and durable, thoroughly efficient and reliable in use and operation, and otherwise well adapted to the purpose for which it is designed.

With the above and numerous other objects in view, as will appear as the description proceeds, the invention resides in certain novel features of construction, and in the combination and arrangement of parts as will be hereinafter more fully described and claimed.

In the drawings:

Figure 1 is a side elevation of an order crane embodying the features of my invention,

Figure 2 is an edge elevation thereof,

Figure 3 is a fragmentary vertical section therethrough,

Figure 4 is a sectional view taken substantially on the line 4-4 of Figure 3,

Figure 5 is a sectional view taken substantially on the line 5-5 of Figure 1,

Figure 6 is a detail view of the lower end of the shank of the hook,

Figure 7 is a view similar to Figure 4 showing another embodiment of the invention, and

Figure 8 is a perspective view of one of the clip members.

Referring to the drawings in detail it will be seen that numeral 5 denotes a standard with an upper U-shaped end 6 having a stationary shaft 7 extending between the terminals thereof. A disk 8 is fixed to the shaft. A pair of plates of circular construction 9 are rotatable on the shaft one to each side of the disk 8 and have a plurality of clips 10 arranged in spaced pairs.

Fillers 11 are disposed between the pairs of clips, and an arcuate filler 12 is disposed between portions of the plates. An arcuate weight element 14 is also disposed between portions of the plates. The disk is formed with a shoulder 15 and the weight 14 is disposed so as to normally urge the plates to rotate in one direction so that a pair of clips 10 as shown in Figure 4 would be adjacent the shoulder 15.

A plurality of order hoops 16 have the extremities of their shanks inserted between the clips and the first one of the hoops has its terminal engaged with the shoulder 15. Therefore when the first one is removed the weight causes the rotation of the plate to put the next order hoop in place and so forth until the final hoop is in place. Instead of the weight 14 the filler 12 may be made larger and the weight eliminated and in this case a spring 14' is anchored to the periphery of the disk and between the plates to attain the same operation and object.

A bracket 20 extends upwardly from one side of the U-shaped end 6 and supports a lamp 21 at the upper end thereof.

It is thought that the construction, operation, utility and advantages of this invention will now be quite apparent to those skilled in this art. To avoid danger to trainmen in leaning out to catch the hoop, an artificial arm similar to the mail train arm can be placed on the train to catch the hoop.

It will be apparent that changes in the details of construction, and in the combination and arrangement of parts may be resorted to without departing from the spirit or scope of the invention as hereinafter claimed or sacrificing any of its advantages.

Having thus described my invention, what I claim as new is:

1. A device of the class described comprising a supporting structure, a shaft on the supporting structure, a pair of plates rotatable on the shaft and means urging said plates to rotate in one direction, clips fixed between the peripheral portions of the plates and arranged in spaced pairs to receive shanks of order hoops, a disk fixed on said shaft with a shoulder formed on said disk with which the extremities of the order hoop shanks may engage.
2. A device of the class described comprising a supporting structure, a shaft on the supporting structure, a pair of plates rotatable on the shaft, clips fixed between the peripheral portions of the plates and arranged in spaced pairs to receive the shanks of order hoops, a disk fixed on said shaft with a shoulder formed on said disk with which the extremities of the order hook shanks may engage, a weight attached to the plates urging rotation of said plates as the order hoops are released from the clip, so that said order hoops will be successively and automatically placed in a predetermined position.
3. A device of the class described comprising a shaft, supporting means therefor, a plate rotatable on the shaft, an annular series of clips carried by said plate and adapted to receive the shanks of train order hoops, a member fixed on said shaft, means carried by the plate normally urging the plate to rotate in one direction as the order hoops are released from the clips, so that said order hoops will have the terminals thereof successively brought into engagement with said member for limiting rotation of said plate in said one direction.

In testimony whereof I affix my signature.
BRAYTON M. PERKINS.
